UNITED STATES PATENT OFFICE.

WILHELMUS ADRIANUS VAN BERKEL, OF ROTTERDAM, NETHERLANDS, ASSIGNOR
TO U. S. SLICING MACHINE COMPANY, OF LAPORTE, INDIANA, A CORPORATION
OF INDIANA.

MEAT-SLICING MACHINE.

Application filed November 6, 1922. Serial No. 599,457.

To all whom it may concern:

Be it known that I, WILHELMUS ADRIANUS VAN BERKEL, manufacturer, a subject of the Queen of the Netherlands, residing at Rotterdam, Prinses Julianalaan 77, Netherlands, have invented certain new and useful Improvements in Meat-Slicing Machines, of which the following is a specification.

10 The present invention relates to a meat slicing machine of the kind in which the meat or the like to be sliced is reciprocated on a horizontal slide along a circular shaped, vertically positioned knife, rotating about 15 a horizontal axis.

In machines of this kind the rotating knife is driven by a chain running over two chain wheels, which driving mechanism is covered by a vertical column extending out- 20 side the machine.

Though in this way the driving means for the knife are suitably built in the machine, the hitherto known construction has the disadvantage that the space next to the 25 sliced meat receiving table or the like is almost entirely occupied by the vertical column, which gives rise to various difficulties.

It has already been proposed to remove 30 this disadvantage by locating the driving chain in a curved hollow arm, the chain being guided over sets of guiding rollers arranged within the said arm. This construction, however, is complicated and has the 35 disadvantage that a considerably increased driving power is required, as the endless double bent or curved chain can only operate satisfactorily, if it is mounted without any slack.

40 In contradistinction to this construction according to the invention the purpose aimed at is completely attained, without making use of any auxiliary means as e. g. guiding or tension rollers.

45 The invention consists in this that the circular knife and its driving chain, running over two chain wheels located perpendicularly above each other, is mounted in a vertical plate, provided at the front with a horizontal table which adjoins the table 50 located in front of the slide.

Further, according to the invention the vertical plate at the back, namely the side facing the knife, may be provided with an

upstanding or upright sheath surrounding 55 the driving mechanism of the knife, whereas at the side of the plate a broad, forwardly projecting edge may be provided surrounding the table and forming a recess in which e. g. a meat dish may be placed. 60

The annexed drawings illustrate the invention by way of example.

In the drawings—

Fig. 1 is a front elevation of the machine;

Fig. 2 is a plan view of a section over the 65 line II—II in Fig. 1.

The vertical, circular knife 1 rotating about the axis 2, is driven by the endless chain 3, running over the chain wheels 4 and 5 placed perpendicularly above each 70 other.

The knife 1 and its driving mechanism is mounted in the vertical plate 6, which at the front is provided with a horizontal table 7, adjoining the table 9 located in front of the 75 slide. At the back of the plate 6 an up- standing sheath 10 is provided, enclosing the driving mechanism of the knife 1.

At one side of the vertical plate 6 is located a broad, forwardly projecting edge 80 11, extending from the upper to the lower end of the vertical plate 6 and enclosing the horizontal table 7. At the other side of the vertical plate 6 a guide plate 12 is provided, guiding the meat or the like sliced by the 85 knife 1 to the horizontal tables 7 and 9.

As appears from the drawings, the construction according to the invention has the great advantage that the space in front of the knife, which space in the hitherto known 90 devices was occupied by the vertical column, becomes almost entirely available for taking up the sliced meat or the like, whereby the efficiency of the machine is considerably increased. The projecting edge 11 95 forms as it were a recess, in which the largest dishes may be placed. Owing to the chain wheels for driving the circular knife being located perpendicularly above each other and the endless chain being operated 100 without the use of guiding or tension rollers, the driving of the circular knife requires but a very small exertion of power.

What I claim as my invention is:

1. In a slicing machine, a rotary knife, 105 a table arranged to reciprocate at one side of said knife to present material thereto, a horizontal slice receiving table located at

the opposite side of said knife from said reciprocating table, said receiving table extending past the vertical center of said knife, and a support for said knife interposed between said receiving table and said knife.

2. A slicing machine comprising a rotary knife, a web for supporting said knife substantially parallel to the plane of said knife and arranged adjacent one face thereof, and a brace for said web extending at an angle from the plane thereof to support said web against lateral stress, the space between said web and brace being open to receive slices formed by said knife.

3. A slicing machine comprising a disc knife, a bearing for supporting said knife comprising a web positioned adjacent one face of said knife and substantially parallel to the plane thereof, means for driving said knife interposed between said web and said knife, and a slice receiving tray extending beneath said bearing at the side of said web opposite said knife.

4. A slicing machine comprising a disc knife, a bearing for supporting said knife, driving means for said knife extending downwardly therefrom adjacent one face thereof, a support for said bearing comprising a web having a housing at the side thereof adjacent said knife for containing said driving means, and a brace for said web at the side thereof opposite said housing, said brace being offset from the vertical center of said knife to provide an open space for receiving slices formed by said knife.

5. A slicing machine comprising an upright disc-shaped knife, a table arranged to reciprocate adjacent one face of said knife to present material thereto to be sliced, a bearing for supporting said knife, a receiving table for slices extending beneath said bearing at the side of said knife opposite said reciprocating table, and a support for said bearing interposed between said knife and said receiving table.

6. A slicing machine comprising an upright disc knife, a reciprocating table movable adjacent one face of said knife for presenting material thereto, a bearing for said knife, a receiving table positioned adjacent said knife opposite said reciprocating table and extending beneath said bearing, a support for said knife comprising a web interposed between said knife and said receiving table, said web having a housing at the side, thereof adjacent said knife and extending downwardly from said bearing, and driv-

ing mechanism positioned in said housing.

7. A slicing machine comprising an upright disc knife, a reciprocating table movable adjacent one face of said knife for presenting material thereto, a bearing for said knife, a receiving table positioned adjacent said knife opposite said reciprocating table and extending beneath said bearing, a support for said knife comprising a web interposed between said knife and said receiving table, said web having a housing at the side thereof adjacent said knife and extending downwardly from said bearing, driving mechanism positioned in said housing, and a brace plate connected with said supporting web on the side thereof opposite said knife, said brace plate being offset relative to the vertical center of said knife to provide space for said receiving table.

8. In a slicing machine, a vertically disposed disc-shaped knife, a bearing for supporting said knife, and a support for said bearing comprising a web member arranged substantially parallel with the plane of said knife and extending downwardly from said bearing, said web member being spaced from said knife to provide clearance for driving means directly beneath said bearing, and a bracing member for said web arranged at an angle thereto and offset relative to the vertical center of said knife to provide clearance on the side of said web opposite said knife for receiving slices.

9. A slicing machine comprising a vertically arranged rotary disc knife, a reciprocating table movable adjacent one face of said knife for presenting material thereto, a receiving table extending past the vertical center of said knife adjacent the side thereof opposite said reciprocating table, a bearing for said knife, a support for said bearing comprising an upright plate interposed between a portion of said receiving table and said knife, said plate having a housing at the side thereof adjacent said knife and directly beneath said bearing, driving means for said knife positioned in said housing, and a web for bracing said supporting plate, said web being offset relative to the vertical center of said knife and extending at an angle to said supporting plate, the space between said web and supporting plate being open to accommodate said receiving table and to permit the deposits of slices on said receiving table below the axis of said knife.

In testimony whereof I affix my signature.

WILHELMUS ADRIANUS van BERKEL.
